UNITED STATES PATENT OFFICE.

WALTER FENTON, OF MANCHESTER, ENGLAND, ASSIGNOR TO UNDERWOOD TYPE-WRITER COMPANY, OF NEW YORK, N. Y., A CORPORATION OF DELAWARE.

TYPEWRITING-MACHINE.

1,327,908.

Specification of Letters Patent. Patented Jan. 13, 1920.

Application filed September 19, 1917. Serial No. 192,052.

To all whom it may concern:

Be it known that I, WALTER FENTON, a subject of the King of Great Britain, residing at 2 Adria road, Dedsbury, Manchester, in the county of Lancaster, England, have invented new and useful Improvements in Typewriting-Machines, of which the following is a specification.

My invention relates to improvements in typewriting machines and particularly to the type of machine described and claimed in United States Patent No. 1,309,322, granted to me July 8, 1919, in which I employ an improved carriage or paper-support comprising two sheet-carriers, one of which may coöperate with either of two platens.

In the said improved type of machine I am enabled to obtain, simultaneously with the typing of an original letter document or other matter, and without removing either the original or copy from the carriage except in cases of substitution as under the fourth head when a fresh original would have to be inserted, the following:

- 25 1. A copy of the whole or of a selected part or parts of the original.
2. Such copy in similar, condensed or extending spacing as compared with the original.
- 30 3. Such copy in similar, reverse or varied order as compared with the original.
4. A summary or list on one sheet of the essential or selected particulars of any original and in any order.
- 35 5. Duplicates of the original or copy or both can be obtained in all cases.

By my present invention I am enabled to obtain all the above and in addition the following:

- 40 6. Typing on any part of the original sheet and giving a carbon impression on any part of the copy sheet.
7. Abolition of carbon sheets if desired except for duplicating the original or copy or both.
- 45 8. Simultaneous visibility, when required, of the original and copy.
9. Direct typing when desired on to any part of the copy sheet.
- 50 10. In carrying my invention into effect I employ the improved carriage with two carriers and a platen bar substantially as described in my aforesaid patent applied to any suitable type of existing typewriter practically all the ordinary parts being re-

tained except the platen roller, and, in addition, I now employ a frame extending on each side of the body of the typewriter, means for disconnecting the two carriers and for sliding the same independently and horizontally along the extended frame to the right and left respectively; and a carbon ribbon or ink ribbon attachment in optional substitution for the ordinary carbon sheet for making copy.

I will now describe an embodiment of my invention with reference to the accompanying three sheets of drawings in which:

Figure 1 is a front elevation of the improved carriage and extended frame.

Figs. 2 and 3 are broken views of Fig. 1 on a larger scale.

Figs. 4 and 5 are sectional views taken on the plane of the line A B, Fig. 3 showing the two carriers and the platen bar in their raised and lowered positions, respectively and also indicating in dotted lines suitable guides for the original and copy sheets.

Figs. 4^a and 5^a are similar views to Figs. 4 and 5, respectively but taken on the line E—F, Fig. 3.

Figs. 6 and 7 are sectional views taken on the line C D, Fig. 3 but omitting certain parts and showing the carbon ribbon attachment in its positions.

Fig. 8 is a sectional elevation showing one of the two end brackets which connect the rollers of the No. 2 carrier.

Figs. 9 and 10 are detail views of the connecting levers of the elevating and depressing attachment.

Fig. 11 is an elevation of one of the two main supporting brackets.

Fig. 12 is a sectional elevation showing one of the two end brackets of No. 1 carrier. In this embodiment I employ

1. A frame attached to the body of the typewriter and consisting of two upright main brackets N connecting which are two square or other suitable rods P and Q placed parallel to each other and at right angles to the brackets. The rods pass through and extend beyond the brackets so that milled disks X X' or knobs or gearing for rotating the same may be attached thereto at one end as shown or at both ends. The rods P and Q are independently revoluble, and by the use of devices presently to be explained, rotation of rod or shaft P will advance or retract a main work-sheet a, while an under-

85

100

105

110

lying work-sheet *b* may be similarly but independently controlled by the rod *Q*. These work-sheets progress along said rods step by step as the types are operated, and one or both of the rods may operate as guide-ways for the sheet-carrying devices.

Where the rods are journaled in the brackets they are rounded to facilitate rotation.

- 10 2. A carrier (No. 1) supported by the rod *P* and consisting of two rollers *D* and *E*, placed parallel to each other and to the rod *Q*, and two intermediate brackets *L*. These brackets travel with the letter-feeding carriage of the typewriter, together with the rollers *D* and *E*, the roller *D* being above the printing point of the typewriter, and the roller *E* being below the printing point, and the outer or main work-sheet *a* running 15 around the lower roller or guide *E* and upwardly to the upper roller or guide *D*, whereby the movements of said work-sheet may be controlled. The rod *P* is parallel with the tracks of the typewriter carriage, 20 and, by turning the finger-piece *X* on the end of said rod, Fig. 2, the upper roll *D* may be revolved and the main work-sheet *a* adjusted accordingly, whereby line-space and other movements of sheet *a* may be produced. The roller *D* slides along the rod or 25 shaft *P*, and the roller *E* may be carried in the lower ends of the brackets *L*, Figs. 2 and 3. The rod or shaft *P* is square, but is mounted at its ends for revolution. The 30 roller *D* may be hollow and in either end is a metal bush with a square center through which the rod *P* passes. The bushes project a short distance and to them are fitted the two brackets *L* which support the roller 35 *E*, which may be solid and of which the pivotal extremities project into and beyond bearings in the brackets *L*. Knobs or equivalent means for rotating the roller *E* when required may be provided. The No. 1 carrier 40 is so arranged that the most forward part of the roller *D* is vertically above and the most forward part of the roller *E* is under and slightly in advance of the typing point of the typewriter. The whole of the 45 parts of this carrier are so arranged that the roller *D* and the rod *P* shall be capable of mutual rotary motion; the roller *E* shall be capable of separate rotary motion; and the whole carrier capable of horizontal motion 50 along the rod *P* within the limits of the frame. The brackets *L* are fixed on a carriage (not shown) connected to the escapement mechanism of the typewriter.
3. A carrier (No. 2) supported by the rod 55 *Q* and consisting of two rollers *A* and *B* placed parallel to each other and to the rod *P* and connected to each other by an endless band *Y* extending practically the full length of the rollers. This carrier No. 2, which is 60 connected to travel with the typewriter carriage, is used partly for the purpose of line-feeding and otherwise controlling a work-sheet *b* which underlies the main work-sheet *a*, and is intended to receive type impressions which are duplicates of those made 70 upon the sheet *a*. These duplicates may be made either by interposition of an ordinary carbon sheet or by the use of a special ink-ribbon mechanism, which will presently be described. The forward roller *B* is a revoluble platen, and occupies a position between the upper and lower rollers *D*, *E*, which control the main work-sheet *a*. As will presently be seen, the platen *B*, which 75 controls the underlying work-sheet *b*, can be dropped out of printing position, so that no duplicates will be made thereon of the type impressions which are produced upon the outer sheet *a*; and a device which supports or backs the sheet *a*, so that it may 80 receive the type impressions at such times, will now be described, with its associated devices. The carrier No. 2 also comprises a metal platen bar *C*, preferably faced with rubber or other suitable material, parallel 85 to the rod *P*, and two end brackets *M*. The roller *A* may be hollow and in either end is a metal bush with a square center through which the rod *Q* passes. The bushes project a short distance and upon them are suspended the two end brackets *M* which support the roller *B* and the platen bar *C*. The roller *B* may be solid and its pivotal extremities project into bearings in the brackets *M*. The whole of the parts of this carrier 90 are so arranged that the roller *A* and the rod *Q* shall be capable of mutual rotary motion which by means of the endless band will be communicated to the roller *B*; and the roller *B* and the platen bar *C* shall be 95 capable of oscillation in a path which is part of the circumference of a circle described about the center of the rod *Q* so that alternately a point on the roller *B* and a point on the platen bar *C* shall be presented at a point which is immediately behind the typing point of the type writer; and further the whole carrier shall be capable of horizontal sliding motion along the rod *Q* within the limits of the frame. 100 The brackets *M* are joined by the platen bar *C* and form a frame hinged to swing up and down in the manner just described. This frame is connectable to the typewriter carriage by means to be presently described, 105 so as to travel with said carriage; said frame, together with the revoluble platen *B*, fixed platen *C* and feed roll *A*, being also capable of independent adjustment in a direction longitudinal of the platens. 110
4. An elevating and depressing attachment supported by the main brackets *N* and consisting of two round rods *R* and *S* placed parallel to each other and to the rods *P* and *Q* and levers *T*, *T'*, *T''* connecting them 115
- 120
- 125
- 130

together, the levers T' being fulcrumed at T' in the end brackets N . The ends of the rods R and S project through slots in the brackets N the rod R passing above the 5 roller D and through two guide rollers H described later. The rod S passes between the roller A and the roller B and through a circular hole in each of the brackets M . The whole of the attachment is so arranged 10 that the rod R can be alternately elevated and depressed in a vertical direction and to a distance regulated by the length of the slots in the brackets N ; that such movements of the rod R shall be communicated by the 15 means of the levers T , T' , T'' , to the rod S so as to cause the rod S to oscillate in a path which is part of the circumference of a circle described about the center of the rod Q ; the rod S in turn communicates motion 20 to or shifts the roller B and the platen bar C by means of the brackets M and so produces the oscillation of the roller B and the platen bar C previously referred to, and into and out of printing position.

25 5. A carbon ribbon or ink ribbon attachment supported by the rod R and the brackets L and consisting of two spools G , two guide rollers H , two ribbon tracks J , and a ribbon guide bar K . The spools G are supported on pivots G' projecting at 30 right angles from the outer sides of the brackets L . The guide rollers H are supported by the rod R which passes through their centers and are placed immediately in front of the two spools G . The guide rollers H are fitted with flanges set apart at a 35 distance equal to the width of the carbon ribbon or ink ribbon. From the guide rollers H are suspended the two tracks J which are maintained in a vertical position immediately under the guide rollers H by means of 40 projections from the brackets L . The ribbon tracks J are cut away at their lower ends at an angle of 45 degrees to enable 45 the ribbon to be doubled around and passed from one ribbon track to the other at right angles to both. The ribbon tracks J are connected at their lower ends by the ribbon guide bar K which passes in front of and 50 parallel to the roller B . This guide bar K has a groove cut in its upper edge along which the carbon ribbon is drawn and which serves to keep the ribbon straight as otherwise it might buckle or curl and so fail to be 55 inserted between the original and copy sheets when the attachment is elevated. The carbon ribbon is placed in position by being wound around the left hand spool from which it passes over the left hand guide 60 roller, down the left hand ribbon track J , along the groove of the ribbon guide bar K , up the right hand ribbon track J , and over the right hand guide roller on to the right hand spool or vice versa. The whole of the 65 attachment is so arranged that, except the

two spools G , it can be alternately elevated and depressed in unison with the rod R ; that when elevated the ribbon guide bar K will hold the ribbon immediately behind a horizontal line drawn parallel to the roller B through the typing point of the type writer, and between the typing point and the most forward point of the roller B ; and that the whole attachment will be capable of horizontal motion along the rod R in 75 company with the carrier No. 1.

6. A device to enable the carrier No. 1 and the carrier No. 2 to be alternately connected to and disconnected from each other. The device consists of a rack F fixed upon and 80 extending the full length of the platen bar C which is part of the carrier No. 2 and a set of teeth W fixed on each of the brackets L which are parts of the carrier No. 1. These sets of teeth W are fixed in such positions on the brackets L that when the platen bar C is elevated they will engage with the rack F thus connecting the two carriers and causing any horizontal spacing motion of the carrier No. 1 to be accompanied by a 85 corresponding horizontal motion of the carrier No. 2 the two carriers moving in company along the rods P and Q . On the platen bar C being depressed the teeth W and rack F become disengaged so that the 90 two carriers are capable of separate horizontal motion.

In operation:—

1. A sheet of paper a to become the original, is placed in the carrier No. 1 by passing it forward under the roller E , then upward in an almost vertical plane in front of the ribbon guide bar K and backward over the roller D , tension springs or clips or any suitable known device being employed 100 to guide and keep the paper a stretched between the rollers D and E as shown in Figs. 4 and 5. It will be seen that the paper-shelf or directrix a' is so constructed and arranged as to insure proper insertion of 110 work.

2. A sheet of paper b to become the copy, is placed in the carrier No. 2 by passing it forward along a directrix or paper-table b' , under the roller A , around the roller B , and 115 backward over the roller A so that it is in contact with the outer side of the endless band.

3. To type on the original sheet and at the same time to obtain a carbon impression on 120 the copy sheet, it is necessary to elevate the roller B and the platen bar C which causes the original sheet and the copy sheet with the carbon ribbon inserted between them to be presented in successive contact at and immediately behind the typing point of the type writer so that on a type key being struck the type will imprint a character on the original sheet a and produce a carbon impression 125 on the copy sheet b .

4. To type on the original sheet *a* without giving a carbon impression on the copy sheet *b* it is necessary to depress the roller *B* and the platen bar *C* which causes the carbon ribbon and the copy sheet to be removed from contact with the original sheet and the platen bar *C* to be brought into contact with the original sheet *a* immediately behind the typing point of the type writer. The platen bar *C* then provides the necessary solidity behind the original sheet so that on a type key being struck the type will imprint a character thereon but will not give an impression elsewhere.
- 15 5. To obtain similar, condensed or extended spacing on the copy as compared with the original:
- a.* Similar spacing,—rotate the rollers *A* and *D* by means of the milled disks *X* *X'* or equivalents in the same direction and to the same extent.
- b.* Condensed spacing,—rotate the roller *A* a less distance than the roller *D*.
- c.* Extended spacing,—rotate the roller *A* a greater distance than the roller *D*.
6. To obtain similar, reverse or varied order on the copy as compared with the original:
- a.* Similar order (forward)—rotate the rollers *A* and *D* in the forward direction. Similar order, (backward) rotate the rollers *A* and *E* in the backward direction.
- b.* Reverse order,—rotate the roller *A* forward and *E* backward or rotate *A* backward and *D* forward.
- c.* Varied order,—vary the direction with or without varying the distance of rotation of the roller *A* on the one hand and either *D* or *E* as required on the other.
- 40 7. To obtain on one copy sheet *b* a summary of particulars extracted from numerous originals it is necessary to retain the copy sheet *b*, in the carrier No. 2 while the various originals are passed through the carrier No. 1, elevating the roller *B* and the platen bar *C* only during the periods in which the selected particulars are being typed on each original sheet *a*.
- 50 8. To obtain duplicate of either original or copy, it is necessary to insert in the particular carrier and behind the original sheet or copy sheet an additional sheet of paper and a sheet of carbon paper—in the manner commonly employed at present.
- 55 9. To type on any selected point of the original sheet *a* and obtain a carbon impression on any selected point of the copy sheet *b*, it is necessary to present the selected points at and immediately behind the typing point of the type writer. This is done by disconnecting the two carriers and sliding each horizontally until the selected points are in vertical line directly behind the typing point and then separately rotating each of the rollers *A* and *D* until the selected points are in such position that on elevating the roller *B*, (which movement also connects the two carriers) they are presented at and immediately behind the typing point of the type writer.
10. The use of a carbon sheet for making the "copy" may be avoided if desired as the invention provides an attachment by which a carbon ribbon or ink ribbon can be automatically inserted between the original sheet and the copy sheet whenever the copy sheet is brought in the position to receive a carbon impression.
11. Simultaneous visibility of the original and copy is obtained by moving the two carriers horizontally in opposite directions until the copy sheet is rendered visible to any extent desired.
12. Direct typing on to the copy sheet is rendered possible by moving the carrier No. 1 entirely to the right or left of the typing point of the type writer so that on a key being struck the type will imprint a character directly on the copy sheet.
- Variations may be resorted to within the scope of the invention, and portions of the improvements may be used without others.
- What I claim and desire to secure by Letters Patent of the United States is:
1. In a typewriting machine, the combination of a carriage, two feed rollers connected thereto for a main work-sheet, two platens also connected to said carriage and means for rotating one of said platens; and a frame extending on each side of the typewriter; 95 said platens and said carriage capable of sliding independently and horizontally along the extended frame to the right and left; all substantially as and for the purposes herein set forth.
- 105 2. In a typewriting machine, in combination, a carriage, a roller and guide thereon for the original or main work-sheet, a carrier connectible to said carriage and comprising a revoluble platen and a platen bar, 100 means for rotating the revoluble platen, and a frame extending on each side of the typewriter; said carrier slidable independently of said carriage and horizontally along the extended frame to the right and left; all 105 substantially as and for the purposes herein set forth.
3. In a typewriting machine, the combination with a carriage consisting of independent sheet-carriers and means for advancing 110 either sheet independently of the other, one of said carriers having two platens shiftable into and out of printing position; of a frame extending on each side of the typewriter; releasable means for connecting the carriers, 115 said carriers being slidable independently and horizontally along the extended frame to the right and left; and a ribbon attach-

ment including means for guiding a ribbon between said sheets; all substantially as and for the purposes herein set forth.

4. The combination of a main work-sheet carrier, means for carrying an underlying work-sheet, and shiftable means to enable the type impressions upon any point of the main sheet either to be duplicated upon any selected portion widthwise or lengthwise of the underlying sheet, or to be made upon said main sheet alone.

5. The combination of a work-sheet carrier; a plurality of platens movable into and out of printing position relatively to said work-sheet carrier; said carrier and said platens being relatively adjustable in a direction longitudinal of the platens.

6. The combination of a letter-feeding carriage having a work-sheet carrier; a carrier having a plurality of platens and adjustable longitudinally of said platens relatively to said work-sheet carrier; said platens being movable into and out of printing position; and means connecting said work-sheet carrier and said platen-carrier to travel together.

7. The combination of a typewriter carriage, a fixed frame having a guideway, means connected to said carriage for carrying a main work-sheet, a carrier slideable along said guideway independently of said carriage and connectible to said carriage in different relative positions; and a plurality of platens upon said carrier movable into and out of printing positions relatively to said main work-sheet.

8. The combination of a typewriter carriage, a fixed frame having a guideway, means connected to said carriage for carrying a main work-sheet, a carrier slideable along said guideway independently of said carriage and connectible to said carriage in different relative positions, and a plurality of platens upon said carrier movable into and out of printing positions relatively to said main work-sheet, one of said platens being revoluble and provided with sheet-feeding means.

9. The combination with a letter-feeding carriage, of relatively shiftable means for carrying main and underlying work-sheets, said means shiftable to enable the type impressions upon the main sheet either to be duplicated upon any selected portion widthwise or lengthwise of the underlying sheet, or to be made upon said main sheet alone; the recited structure including two revoluble work-controlling devices, whereof one is a platen, and also including a revoluble rod mounted upon the machine framework and splined to one of said revoluble devices which is slideable along said rod; said revoluble devices being relatively adjustable longitudinally of said rod, and connectible to travel in unison at different relative ad-

justments; and also including a second platen associated with said revoluble platen; said platens being movable into and out of printing position relatively to said main work-sheet.

10. The combination with a letter-feeding carriage, of relatively shiftable means for carrying main and underlying work-sheets, said means shiftable to enable the type impressions upon the main sheet either to be duplicated upon any selected portion widthwise or lengthwise of the underlying sheet, or to be made upon said main sheet alone; the recited structure including two revoluble work-controlling devices, relatively adjustable longitudinally, for the respective work-sheets; one of said work-controlling devices being a platen; said work-controlling devices connectible to travel in unison with said carriage at various relative adjustments; and also including a second platen associated with said revoluble platen, said platens being movable into and out of printing position relatively to said main work-sheet.

11. In a typewriting machine, the combination of a letter-feeding carriage; means connected to travel therewith, for controlling a main work-sheet; a fixed frame; a guide-rod revolvably mounted upon said fixed frame; and a device slideable along said guide-rod independently of said carriage but connectible to travel therewith; said slideable device including platens movable each into and out of working position relatively to said main work-sheet.

12. In a typewriting machine, the combination of a letter-feeding carriage; means connected to travel therewith, for controlling a main work-sheet; a fixed frame; a guide-rod revolvably mounted upon said fixed frame; and a device slideable along said guide-rod independently of said carriage but connectible to travel therewith; said slideable device including platens movable each into and out of working position relatively to said main work-sheet, one of said platens being revoluble; and a connection being provided between said revoluble platen and said guide-rod, for revolving the platen wherever located along said rod.

13. In a typewriting machine, the combination of a fixed frame; a guide-rod revolvably therein; a feed-roll for a main work-sheet mounted to slide on said rod and splined thereto; means to coöperate with said feed-roll for controlling said work-sheet; a letter-feeding carriage connected to said feed-roll; a second guide-rod revolvble in said fixed frame; a feed roll slideable along said second guide-rod independently of the first-mentioned feed-roll; releasable means to cause said rolls to move together along said rods; two platens associated with said second roll and movable into and out of printing position relatively to the main

- work-sheet; one of said platens associated with said second feed-roll to revolve therewith to control a sheet underlying said main sheet.
- 5 14. In a typewriting machine, the combination of a fixed frame; a guide-rod revoluble therein; a feed-roll splined to said rod; means to cooperate with said roll to feed a main work-sheet; a letter feeding carriage; 10 19 a second guide-rod revoluble in said fixed frame; and a device slideable along said second guide-rod independently of said feed-roll but connectible to travel therewith; said slideable device including platens movable 15 each into and out of printing position relatively to said main work-sheet, one of said platens being revoluble; and a connection being provided between said revoluble platen and said second guide-rod, for 20 revolving the platen wherever located along said rod.
15. The combination with a shiftable frame and a plurality of platens mounted thereon to be shifted alternately into and out of printing position, of a shift-rod engaging said frame, said frame movable along said rod, and means for moving said rod to shift said frame and platens.
16. The combination with a shiftable frame 30 and a plurality of platens mounted thereon to be shifted alternately into and out of printing position, of a shift-rod engaging said frame, said frame movable along said rod, arms whereon said shift-rod is mounted, 35 and means for moving said arms to shift said frame and platens by means of said shift-rod.
17. In a typewriting machine, the combination of a shiftable frame, a plurality of 40 letter-feeding platens mounted thereon to be shifted alternately into and out of printing position, a shift-rod mounted upon the stationary framework of the machine, to engage said shiftable frame at all points in the 45 letter-feeding movement of the latter along said rod, and means for operating said rod and frame to shift said platens.
18. In a typewriting machine, the combination with means for feeding and guiding 50 a sheet, of a plurality of platens, each movable into and out of printing position relatively to said sheet, said platens also shiftable endwise relatively to said sheet-feeding and guiding means.
- 55 19. In a typewriting machine, the combination with means for feeding and guiding a sheet, of a plurality of platens, means for moving either platen into printing position relatively to said sheet and simultaneously 60 moving the other platen out of such printing position, and means for connecting said platens to said sheet-feeding, and guiding means in a plurality of relative adjustments in a direction longitudinal of the platens.
- 65 20. In a typewriting machine, the combination with guides or feeders between which a work-sheet extends, of a plurality of platens mounted between said guides and feeders and movable into and out of printing position relatively to said sheet, and also shiftable endwise relatively to said sheet.
21. In a typewriting machine, the combination with guides or feeders between which a work-sheet extends, of a plurality of platens mounted between said guides and feeders, a carrier whereon said platens are mounted, and whereby either platen may be shifted into printing position and the other out of printing position relatively to said sheet, and means mounted upon the stationary framework of the machine and connected to said carrier to shift said platens.
22. In a typewriting machine, the combination with guides or feeders between which a work-sheet extends, of a plurality of 85 platens mounted between said guides and feeders, and a carrier whereon said platens are mounted, and whereby either platen may be shifted into printing position and the other out of printing position relatively to said sheet, said platens and said guides or feeders relatively adjustable in a direction longitudinal of the platens.
23. In a typewriting machine, the combination with guides or feeders between 90 which a work-sheet extends, of a plurality of platens mounted between said guides and feeders, and a carrier whereon said platens are mounted, and whereby either platen may be carried into printing position and the other out of printing position relatively to said sheet, one of said platens being mounted for revolution, and being also adjustable longitudinally relatively to said guides or feeders.
24. In a typewriting machine, the combination with a plurality of platens, of means independent of said platens for guiding and feeding a work-sheet; each of said platens movable into and out of printing position relatively to said sheet, and means being provided for affording a longitudinal adjustment between one of said platens and said guiding and feeding means.
25. In a typewriting machine, the combination with types and a plurality of 115 platens, of means independent of said platens for guiding and feeding a main work-sheet, means associated with one of said platens for feeding an underlying work-sheet, said sheet-feeding platen and said main sheet guiding and feeding means being relatively adjustable in a direction longitudinal of said platen, and means for enabling the types to cooperate with either platen.
26. In a typewriting machine, the combination with types and a plurality of 120 platens, of means independent of said platens for guiding and feeding a work-sheet, and means for enabling the types to 125

cooperate with either platen in typing said work-sheet, one of said platens being revolute and provided with means for carrying and feeding a work-sheet independently of 5 the first work-sheet, and means being provided to afford relative lateral adjustment between said guiding and feeding means and said revolute platen.

27. The combination with a plurality of 10 relatively movable frames connected together for relative movements in two directions, of a plurality of platens carried by one of said frames, and means carried by the other of said frames for guiding and 15 feeding a work-sheet for coöperation with either of said platens.

28. The combination of a revolute platen and a fixed or non-rotating platen closely placed one above the other, and upper and 20 lower sheet-feeding or guiding means between which said platens are mounted; said platens movable relatively to said sheet-feeding means, to bring either platen to printing position, and said revolute platen 25 adjustable endwise relatively to said sheet-feeding means.

29. In a typewriting machine, the combination with means for feeding and guiding a sheet, of a plurality of platens, each 30 movable into and out of printing position relatively to said sheet, and means for supporting an ink ribbon between said sheet and one of said platens.

30. In a typewriting machine, the combination with means for feeding and guiding a main sheet, of a plurality of platens, one of which is revolute, means for moving either platen into printing position relatively to said sheet and simultaneously moving 40 the other platen out of such printing position, and means for feeding an ink ribbon along said revolute platen in rear of the main sheet.

31. In a typewriting machine, the combination with guides or feeders between which a work-sheet extends, of a plurality of platens mounted between said guides and feeders and shiftable into and out of printing position relatively to said sheet, and 50 means shiftable with one of said platens into and out of printing position, for carrying an ink ribbon in front of such platen.

32. In a typewriting machine, the combination with guides or feeders between which a work-sheet extends, of a plurality of platens mounted between said guides and feeders, a carrier whereon said platens are mounted, and whereby either platen may be carried into printing position and the other 60 out of printing position relatively to said sheet, and an ink ribbon guiding-device upon said carrier for coöperation with one of said platens.

33. In a typewriting machine, the combination with a plurality of platens, of means

independent of said platens for guiding and feeding a work-sheet; each of said platens shiftable into and out of printing position relatively to said sheet, and an inking ribbon-carrier to coöperate with one of said platens and shiftable therewith.

34. In a typewriting machine having a letter-feeding carriage, the combination with types and a plurality of platens associated with said carriage, of means independent of 75 said platens but also associated with said carriage for guiding and feeding a work-sheet, means for enabling the types to coöperate with either platen in typing said work-sheet, and means upon said carriage 80 for carrying an ink ribbon to coöperate with one of said platens.

35. The combination with a plurality of relatively movable frames connected together, of a plurality of platens carried by 85 one of said frames, means carried by the other of said frames for guiding and feeding a work-sheet for coöperation with either of said platens, and means upon one of said frames for carrying an ink ribbon to coöperate with only one of said platens.

36. The combination of a revolute platen and a fixed or non-rotating platen closely placed one above the other, upper and lower sheet-feeding or guiding means between 95 which said platens are mounted; said platens shiftable relatively to said sheet-feeding means, to bring either platen to printing position, and ink-ribbon guiding-means to coöperate with said revolute platen.

37. In a typewriting machine, the combination with a carriage, of a revolute platen having sheet-feeding means and connected to said carriage, and an ink-ribbon guiding and feeding device connected to travel with 105 said carriage and associated with said platen, said platen shiftable together with the ribbon into and out of printing position.

38. In a typewriting machine, the combination with a carriage, of a revolute platen having sheet-feeding means and connected to said carriage, an ink-ribbon guiding and feeding device connected to travel with said carriage and associated with said platen, said platen shiftable together with the ribbon into and out of printing position, a second platen shiftable into and out of printing position, and means for carrying a work-sheet to coöperate with either platen.

39. In a typewriting machine, the combination with a carriage, of a revolute platen having sheet-feeding means and connected to said carriage, an ink-ribbon guiding and feeding device connected to travel with said 125 platen, said platen shiftable together with the ribbon into and out of printing position, a second platen shiftable into and out of printing position, and means for carrying a work-sheet to coöperate with either 130

platen, said work-sheet carrying means and the revoluble platen being relatively adjustable in a direction longitudinal of the platen.

40. In a typewriting machine, the combination of a letter-feeding carriage having upper and lower feeding and guiding means for carrying a work-sheet extending up and down between them, means connected to said carriage for carrying and feeding a ribbon 10 extending along the rear of said work-sheet between said feeding and guiding means, a plurality of platens also connected with said carriage and mounted between said feeding and guiding means, and means for shifting either platen into printing position and the other out of printing position relatively to said work-sheet.

41. In a typewriting machine, the combination of a letter-feeding carriage having upper and lower feeding and guiding means for carrying a work-sheet extending up and down between them, means connected to said carriage for carrying and feeding a ribbon extending along the rear of said work-sheet 25 between said feeding and guiding means, a plurality of platens also connected with said carriage and mounted between said feeding and guiding means, means for shifting either platen into printing position and the other out of printing position relatively to said work-sheet, and means for affording a relative adjustment between said carriage and said platens in a direction longitudinal of the platens.

42. In a typewriting machine, the combination of a letter-feeding carriage having upper and lower feeding and guiding means for carrying a work-sheet extending up and down between them, means connected to said carriage for carrying and feeding a ribbon 40 extending along the rear of said work-sheet between said feeding and guiding means, a plurality of platens also connected with said carriage and mounted between said feeding and guiding means, one of said platens being revoluble and provided with sheet-controlling devices, and means for shifting said revoluble platen into and out of printing position together with said ribbon, and for 45 shifting the other platen into and out of printing position.

43. In a typewriting machine, the combination of a letter-feeding carriage having upper and lower feeding and guiding means 55 for carrying a work-sheet extending up and down between them, means connected to said carriage for carrying and feeding a ribbon extending along the rear of said work-sheet between said feeding and guiding means, a plurality of platens also connected with said carriage and mounted between said feeding and guiding means, one of said platens being revoluble and provided with sheet-controlling devices, means for shifting 60 said revoluble platen into and out of print,

ing position together with said ribbon and for shifting the other platen into and out of printing position, and means for affording a relative adjustment between said carriage and said platens in a direction longitudinal of the platens. 70

44. In a typewriting machine, the combination with a carriage and a revoluble platen, of a ribbon guiding and feeding mechanism connected with said carriage to travel therewith, including means for guiding the ribbon in front of said platen, means to shift the platen, with reference to the carriage, and the ribbon-guiding means into and out of printing position, and means to connect said platen with said carriage to travel therewith when the former is shifted to printing position. 75

45. In a typewriting machine, the combination with a carriage having a revoluble platen, of a ribbon guiding and feeding mechanism connected with said carriage to travel with said carriage, including means for guiding the ribbon in front of said platen, means to shift the platen into and out of printing position together with the ribbon, and means also connected with said carriage for carrying a work-sheet in front of said ribbon and independently of said platen. 80

46. In a typewriting machine, the combination with a carriage having a revoluble platen, of a ribbon guiding and feeding mechanism connected with said carriage to travel with said carriage, including means for guiding the ribbon in front of said platen, means to shift the platen into and out of printing position together with the ribbon, means also connected with said carriage for carrying a work-sheet in front of said ribbon and independently of said platen, and a second platen also shiftable into and out of printing position. 100

47. In a typewriting machine, the combination with a carriage having a revoluble platen, of a ribbon guiding and feeding mechanism connected with said carriage to travel with said carriage, including means for guiding the ribbon in front of said platen, means to shift the platen into and out of printing position together with the ribbon, means also connected with said carriage for carrying a work-sheet in front of said ribbon and independently of said platen, a second platen also shiftable into and out of printing position, and means for affording a relative shift between said revoluble platen and said carriage in a direction longitudinal of the carriage. 110

48. In a typewriting machine having a carriage, the combination of a lower guide over which a main work-sheet turns upwardly below the printing point, an upper guide over which the main sheet turns backwardly above the printing point, certain of 115 120 125 130

said guides being revoluble, a directrix for said main work-sheet extending from the rear downwardly and forwardly to the lower guide and upwardly therefrom in front of said main work-sheet, a plurality of platens mounted between said guides and shiftable into and out of printing position relatively to said main sheet, one of said platens being revoluble, and a directrix for 10 an underlying work-sheet forward of the first-mentioned directrix and extending downwardly and forwardly beneath said revoluble platen.

49. In a typewriting machine, the combination of a letter-feeding carriage, upper guiding means above the printing point and lower guiding means below the printing point for guiding a main work-sheet up past the printing point, a plurality of platens 15 between said upper and lower guiding means, means coöoperating with one of said platens for carrying an underlying work-sheet, means for shifting either platen into printing position, and means for feeding an ink-ribbon between said work-sheets.

50. In a typewriting machine, the combination of a letter-feeding carriage, upper guiding means above the printing point and lower guiding means below the printing point for guiding a main work-sheet up past the printing point, a plurality of platens 20 between said upper and lower guiding means, means coöoperating with one of said platens for carrying an underlying work-sheet, means for shifting either platen into printing position, and means for feeding an ink-ribbon between said work-sheets,

means coöoperating with one of said platens for carrying an underlying work-sheet, means for shifting either platen into printing position, and means for feeding an ink-ribbon between said work-sheets, said ink-ribbon feeding means being connected to said carriage to travel therewith. 35

51. In a typewriting machine, the combination of a letter-feeding carriage, upper guiding means above the printing point and lower guiding means below the printing point for guiding a main work-sheet up past the printing point, a plurality of platens 40 between said upper and lower guiding means, means coöoperating with one of said platens for carrying an underlying work-sheet, means for shifting either platen into printing position, and means for feeding an ink-ribbon between said work-sheets, said ink-ribbon feeding means being connected to said carriage to travel therewith, and constructed to shift into and out of printing position together with said work-sheet- 45 carrying platen.

In testimony whereof I have signed my name to this specification in the presence of two subscribing witnesses.

WALTER FENTON.
